QUICK RELEASE SEAR FOR LIGHT MACHINE GUNS

Richard H. Colby, South Hadley, Mass., assignor to the
United States of America as represented by the Secretary
of the Army

Filed Oct. 5, 1960, Ser. No. 60,759

5 Claims. (Cl. 42—69)
(Granted under Title 35, U.S. Code (1952), sec. 266)

The invention described herein may be manufactured and used by or for the Government for governmental purposes without the payment of any royalty thereon.

This invention relates to automatic firearms and more particularly to the trigger mechanisms thereof.

One of the hazards oftentimes encountered with automatic firearms is a run-away gun where the operator loses control of the firing because the sear and/or the sear notch in the sear controlled member are worn to the extent that the operating mechanism cannot be stopped by the sear when released by the trigger mechanism.

One of the causes of this excessive wear is that the operators generally do not return the trigger to nonfiring position quickly enough to prevent rasping contact between the searing portions before complete searing is achieved. In the past, devices have been provided which achieve a quick release of the sear by mechanical means, but these devices are actuated by the operating member controlled by the sear and are generally complicated in design and operation.

It is, therefore, the principal object of this invention to provide a quick release sear which is controlled entirely by the cooperating trigger and which is released with the same speed regardless of how slowly the trigger is released by an operator.

It is also the purpose of this invention to provide a quick release sear which is simple in design, easy to manufacture and is positive in operation.

The specific nature of the invention as well as other objects and advantages thereof will clearly appear from a description of a preferred embodiment as shown in the accompanying drawings in which:

FIG. 1 is a longitudinally cross-sectioned view of the trigger mechanism of this invention showing the trigger in normal position and the operating rod latched in the recoil position thereof by the sear;

FIG. 2 is a view similar to FIG. 1 but showing the trigger actuated to the firing position and the sear in its disengaged position;

FIG. 3 is a view taken along line 3—3 of FIG. 1;

FIG. 4 is a view taken along line 4—4 of FIG. 2; and

FIG. 5 is a perspective, exploded view of the trigger mechanism.

Shown in the figures is a light machine gun 12 having a reciprocal operating rod 14 which is arranged for actuating the operating mechanism (not shown) of the gun and which is actuatable in recoil and counterrecoil strokes between a recoil and a battery position. Operating rod 14 is spring-biased by conventional means (not shown) to the battery position and is releasably held in the recoil position by a trigger mechanism 16 mounted on the underside of a receiver 18.

Trigger mechanism 16 includes a trigger housing 20 having a longitudinal channel 22 disposed along the top thereof in which channel a sear 24 and a trigger 26 are mounted for cooperation as hereinafter described. A trigger guard 28 is provided at the bottom front end of trigger housing 20 to form a clearance 30 into which a fingerpiece 32 of trigger 26 depends to provide means for manual actuation thereof as hereinafter described. The rear side of clearance 30, noted at 34, extends vertically downward in trigger housing 20 from the bottom of

channel 22. As trigger housing 20 may be fabricated from a light and relatively soft metal, there is provided at the junction of side 34 and the bottom of channel 22 an insert 36 which is made of steel and which has a purpose to be more fully explained hereinafter. Insert 36 forms a longitudinal ledge 38 and a front face 40 which extends downwardly at right angles from the front edge thereof.

Sear 24 is of bar configuration with a rectangular cross-section and is longitudinally disposed in channel 22 immediately below operating rod 14. Sear 24 is rockingly mounted approximately midway the length thereof on a transverse pin 42 so as to be pivotal between an engaging and a disengaged position. The rear end of sear 24 forms a latch portion 44 which, when the sear is in the engaging position, is receivable by a notch 46 in operating rod 14 for releasably securing the operating rod in the recoil position. A spring 48 is disposed between the underside of sear 24, rearwardly of pin 42, and the bottom of channel 22 for biasing the sear to the engaging position.

Provided vertically through sear 24 forwardly of pin 42 is a rectangular aperture 52 which receives a sear latch 54. Sear latch 54 is mounted in aperture 52 by means of a transverse axle 56 so as to be pivotal between a blocking and a release position. The lower end of sear latch 54, noted at 58, extends below sear 24 so as to be engageable with ledge 38 of insert 36 so that, when the sear latch is in the blocking position, sear 24 is prevented from moving out of the disengaged position. When sear latch 54 is in the release position, lower end 58 thereof is swung clear of ledge 38 and is displaced downwardly along front face 40 thereof to permit actuation of sear 24 by spring 48 to the position in engagement with operating rod 14. A spring 60 is disposed between sear latch 54, above axle 56, and the rear wall of aperture 52 for biasing the sear latch to the blocking position.

Trigger 26 includes a substantially rectangular body portion 62 from which fingerpiece 32 integrally depends. Trigger 26 is pivotally mounted in trigger housing 20 forwardly of sear latch 54 and below the front end of sear 24 by means of a pin 64 which traverses channel 22 and the front upper corner of body portion 62. Fingerpiece 32 extends into clearance 30 by means of an opening 66 which provides communication between such clearance and channel 22. A vertical recess 68 bifurcates longitudinally the top rear corner of body portion 62 and such recess receives a roller 70 which is axially mounted on a transversal shaft 72 and is disposed so as to project above the top of trigger 26 for rolling contact with the underside of the front end of sear 24. Whereby, when fingerpiece 32 is pulled rearwardly, trigger 26 pivots about pin 64 to raise roller 70 against the front end of sear 24 which is pivoted thereby from the engaging to the disengaged position.

A spring-biased plunger 74 is housed within fingerpiece 32 and is arranged so as to press against side 34 of clearance 30 for biasing trigger 26 forwardly from a firing to a nonfiring position. The end of fingerpiece 32 is received by a recess 76 in trigger guard 28 and the engagement of the fingerpiece with the ends of the recess limits the movement of trigger 26 between the firing and nonfiring positions thereof.

A pair of wings 78 extend rearwardly from the sides of body portion 62 so as to be laterally spaced and such wings are connected at the rear ends by a laterally disposed bar 80. Bar 80 is spaced rearwardly from the rear end of body portion 62 sufficiently to form a clearance 82 for receiving lower end 58 of sear latch 54 and is disposed to pull such lower end from ledge 38 during the return of trigger 26 to the nonfiring position.

Thus, when trigger 26 is in the nonfiring position and operating rod 14 is latched in the recoil position thereof, as illustrated in FIG. 1, sear latch 54 is positioned by

bar 80 on the trigger so that lower end 58 of the sear latch is pulled forwardly off ledge 38 and displaced downwardly along front face 40 thereof. When fingerpiece 32 is pulled rearwardly to fire gun 12, roller 70 is raised against the underside of the front end of sear 24 to disengage latch portion 44 from notch 46 and thereby release operating rod 14 to initiate a burst of fire. When the front end of sear 24 is elevated by trigger 26, sear latch 54 is also elevated so that, when the sear reaches the disengaged position, lower end 58 of the sear latch is raised clear of front face 40 of ledge 38. Whereupon, sear latch 54 is biased to the blocking position by spring 60 so that lower end 58 is rearwardly displaced over ledge 38. Consequently, when fingerpiece 32 is permitted to go forwardly to stop the firing burst, the contact of lower end 58 with ledge 38 blocks the pivotal displacement of sear 24 from the disengaged position until trigger 26 is displaced sufficiently for bar 80 to pull the lower end of latch 54 from ledge 38. When lower end 58 is pulled clear of ledge 38 by bar 80, sear 24 is instantly freed to be pivoted to the engaged position for stopping the reciprocation of operating rod 14 through the bias of spring 48.

From the foregoing it is clearly apparent that there is provided herein for a trigger mechanism a quick release sear which is positive in operation, simple in design and is easy to manufacture.

Although a particular embodiment of the invention has been described in detail herein, it is evident that many variations may be devised within the spirit and scope thereof and the following claims are intended to include such variations.

I claim:

1. In a machine gun having a reciprocating member, a trigger mechanism including a trigger housing, a sear pivotally mounted in said trigger housing for releasable engagement with the reciprocating member for initiating and stopping operation of the gun, a trigger pivotally disposed in said trigger housing for operational cooperation with said sear to transfer displacement of said trigger to a firing position into pivotal displacement of said sear to a position in disengagement from the member, a ledge formed in said trigger housing, a sear latch pivotally carried by said sear, said sear latch being disposed for releasable engagement with said ledge for blocking movement of said sear into engagement with the member, and means carried by said trigger for pulling said sear latch off said ledge for quick release of said sear into engagement with the member responsive to pivotal displacement of said trigger from the firing position.

2. In a machine gun having a reciprocating member, a trigger mechanism including a trigger housing, a sear pivotally mounted in said trigger housing for releasable engagement with the member for initiating and stopping operation of the gun, means for biasing said sear to a position for engagement with the member, a trigger mounted in said trigger housing for pivotal displacement between a firing and a nonfiring position, means on said trigger for converting displacement thereof to the firing position to pivotal displacement of said sear to a position out of engagement with the member, a sear latch mounted on said sear for pivotal displacement between a blocking and a release position, means for biasing said sear latch to the blocking position, a ledge formed in said trigger housing so as to be contactable by said sear latch when in the blocking position for releasably holding said sear

in the disengaged position thereof, and means carried by said trigger for pulling said sear latch out of contact with said ledge responsive to displacement of said trigger from the firing position for quick release of said sear to the position for engagement with the member.

3. The trigger mechanism as defined in claim 2 wherein said trigger includes a substantially rectangular body pivotally mounted in said trigger housing by means of a pin which is transversely disposed through said trigger housing and through said body at the front top corner thereof, a vertical recess disposed for bisecting longitudinally the top rear corner of said body, and a roller axially mounted in said recess so as to be displaceable against said sear for converting pivotal displacement of said trigger to the firing position to pivotal displacement of said sear to a position out of engagement with the member.

4. The trigger mechanism as defined in claim 2 wherein said sear is provided with a vertically disposed aperture therethrough, said sear latch is pivotally mounted in said aperture for displacement between the blocking and release positions thereof and a spring is disposed between said sear latch and a wall of said aperture for biasing said sear latch to the blocking position.

5. In a machine gun having a reciprocating member, a trigger mechanism including a trigger housing provided with a channel disposed longitudinally along the top thereof, a sear mounted in said channel on a first pin disposed transversely through said sear approximately midway the length thereof for pivotal displacement between an engaging and a disengaged position, a latch portion disposed at the rear end of said sear for releasable engagement with a notch in the member for stopping the reciprocation thereof when said sear is in the engaging position, a trigger including a substantially rectangular body and a fingerpiece depending therefrom, a second pin extending transversely through said channel and said body at the top front corner thereof to provide pivotal displacement of said trigger from a firing to a nonfiring position, a vertically disposed recess for bisecting longitudinally the top rear corner of said body, a roller axially mounted on a shaft transversely disposed through said recess, said roller being engageable with the underside of said sear forwardly of said first pin for transferring pivotal displacement of said trigger to the firing position to pivotal displacement of said sear to the disengaged position, an aperture vertically disposed through said sear forwardly of said first pin, a sear latch mounted in said aperture on a transversal axle for pivotal displacement between a blocking and a release position, a spring disposed between said sear latch and a wall of said aperture for biasing said sear latch to the blocking position, a ledge disposed in said trigger housing so as to be engageable by said sear latch when in the blocking position to prevent movement of said sear to a position in engagement with the member, and a bar disposed on said trigger for displacement against said sear latch for pulling said sear latch clear of said ledge to the release position for quick release of said sear to the engaged position during displacement of said trigger to the nonfiring position.
